(57) **CLAIM**

The ornamental design for a transformable crutch as shown and described.

DESCRIPTION

2.1 is a front view of a transformable crutch in a configuration of normal crutch;

2.2 is a back view thereof;

2.3 is a left view thereof;

2.4 is a right view thereof;

2.5 is a top view thereof;

2.6 is a bottom view thereof;

2.7 is a perspective view thereof;

2.8 is a front view of the transformable crutch in a configuration for sitting;

2.9 is a back view thereof;

2.10 is a left view thereof;

2.11 is a right view thereof;

2.12 is a top view thereof;

2.13 is a bottom view thereof;

2.14 is a perspective view thereof;

2.15 is a front view of the transformable crutch in a storage configuration;

2.16 is a back view thereof;

2.17 is a left view thereof;

2.18 is a right view thereof;

2.19 is a top view thereof;

2.20 is a bottom view thereof; and

2.21 is a perspective view thereof;

The broken lines illustrate portions of the crutch that form no part of the claimed design.

1 Claim, 17 Drawing Sheets
